UNITED STATES PATENT OFFICE.

WILLIAM K. MEYER, OF NEW YORK, N. Y.

NECKTIE.

Application filed May 26, 1923. Serial No. 641,689.

To all whom it may concern:

Be it known that I, WILLIAM K. MEYER, a citizen of the United States of America, residing at New York, in the county of 5 New York and State of New York, have invented certain new and useful Improvements in Neckties, of which the following is a specification.

My invention relates to improvements in 10 neckties, and is especially applicable to the four-in-hand type; and has for its object the construction of a tie in such a manner that its original shape will not be destroyed by the strain incident to tying and 15 adjusting it.

A further object of my invention is the construction of the larger tying end of the tie of elastic material and the construction of the smaller tying end and the neckband 20 in such a manner that those parts are substantially non-elastic.

A still further object of my invention is the construction of a tie with the larger 25 tying end having an elastic lining therein, and the smaller tying end with a non-elastic lining therein.

A still further object of my invention is the construction of a tie having the lining in the larger end thereof cut on the bias 30 and the lining in the smaller tying end cut straight.

With these and further objects in view, one embodiment of my invention is disclosed in the accompanying drawings, in 35 which:—

Figure 1 is a top plan view;

Figure 2 is a bottom plan view, with parts of the tie broken away;

Figure 3 is a vertical longitudinal section;

Figure 4 is a section on the line 4—4 of Figure 2;

Figure 5 is a section on the line 5—5 of Figure 2; and

Figure 6 is a section on the line 6—6 of Figure 2.

The tie shown in the accompanying drawings is the well-known form of four-in-hand tie, consisting of two pieces of silk or other 50 material usually cut on the bias, this manner of cutting rendering the silk elastic, the material being folded to form a larger tying end 1 and a smaller tying end 2. These two parts are joined by a bias seam 55 3. The ends of the pieces joined constitute a narrow neckband 4.

The larger tying end has a lining 5 of elastic material. The material constituting this lining may be cut on the bias in order to make it elastic, or it may be a material 60 so woven as to be elastic. In other words, this lining may have the warp and weft threads extending diagonally of the tie. On top of the lining 5 may be placed a narrow reinforcing band 6 of elastic material, 65 similar to the material of the lining 5. The smaller tying end and the neckband have a lining 7 of inelastic material, such as material cut straight. This material may be heavier than the material of the lining of the larger tying end and may be of flannel, canton flannel, or other similar material. It may have the warp and weft threads extend at right angles and parallel to the longitudinal axis of the tie. The lining and band in the larger tying end are loosely 70 stitched together, as indicated at 8, and to the fold of the silk or other outer material. The thread 8 is extended a short distance 75 beyond the end of the lining and knotted as shown at 9. This construction permits the silk, lining, and band to be stretched without breaking the stitching or the fabric and, because of the elasticity of all three of the parts and the character of the stitching, 80 enables the larger tying end to resume its original shape after the pulling strain is removed. The lining is stitched to the turned-in parts of the smaller tying end as indicated at 10, and the edges of the smaller 85 tying end and a part of the neckband are stitched on the edge through the lining and material as indicated at 11, this stitching entirely through the smaller tying end extending from point 12 to point 13. The 90 construction of the band and smaller tying end which has been described enables these parts of the tie to withstand the pulling strain of adjustment and tying without injury to the outer silk material. It also prevents the band and smaller end from becoming "stringy" or distorted. The point of connection between the elastic lining and the non-elastic lining is indicated by stitching at 14.

The advantages of a tie made in accordance with my invention will be apparent from the description given. The smaller end of the tie and the neckband, which are the weakest parts and which must be pulled 100 between the folds of the ordinary turned-down collar, are prevented from being dis-

torted or pulled out of shape by the non-
elastic lining and the edge stitching. The
construction of this end of the tie and of the
neckband enables either to be used as a place
for attachment of the small label, usually of
silk, containing the name of the manufacturer
and such other information as is
usually given on such labels. The lining
used for this part of the tie enables it to
10 be tied into a firm and good appearing knot.

The construction of the larger tying end
prevents injury from any pulling strain to
which it may be subjected, due to the elastic
material and character of stitching. The
15 silk and lining may be stretched and, being
elastic, will resume their normal condition
after the pulling strain is removed. Allowing
some length of the thread of the loose
stitching beyond the point where it is in-
20 serted in the material enables the stitches
to be changed in length without breaking
them.

Having described my invention, what I
claim and desire to protect by Letters Patent is:

1. A necktie comprising two tying ends
and a neckband consisting of folded material,
said material being elastic, and
a lining for each end, the lining of
30 one end consisting of material elastic
in the direction of the length of the tie,

said elastic lining material being loosely
stitched to the folded material, and the lining
of the other end consisting of inelastic
material, said inelastic lining being joined 35
to said folded material by stitching extending
through said lining and said folded material
whereby the smaller tying end of said
tie is rendered non-elastic in the direction
of the length of the tie. 40

2. A necktie comprising two tying ends
and a neckband made of folded material,
said material being elastic, a lining for each
end, the lining of one end consisting of
material elastic in the direction of the 45
length of the tie, and a reinforcing band of
elastic material placed on the elastic lining,
said elastic lining and reinforcing band being
loosely stitched to the folded material,
and the lining of the other end consisting 50
of inelastic material, said inelastic lining
being joined to said folded material by
stitching extending through said lining and
said folded material whereby the smaller
tying end of said tie is rendered non-elastic 55
in the direction of the length of the tie.

In testimony whereof I affix my signature.

WILLIAM K. MEYER.
